UNITED STATES PATENT OFFICE

1,998,887

AUTOMATIC FUEL REGULATOR

Charles Lawrence Stokes, Los Angeles, Calif., assignor, by mesne assignments, to Lynn A. Williams, Evanston, Ill., and Clifford C. Bradbury, Glencoe, Ill., successor trustees

Original application March 22, 1923, Serial No. 626,990, now Patent No. 1,694,801, dated December 11, 1928. Divided and this application September 21, 1928, Serial No. 307,401

3 Claims. (Cl. 123—119)

My invention relates to improvements in automatic priming and carbureting devices for internal combustion engines.

The principal object of my invention is to provide means for automatically feeding a preliminary rich charge in order to start an internal combustion engine, and thereafter automatically reducing the richness of the charge.

I am enabled to do this by utilizing the heat 10 of the engine itself for the purpose of actuating suitable heat responsive mechanism.

The ordinary means of priming an engine for starting, generally consists of what is known as a choke whereby, by cutting off the supply of air 15 to the carburetor, a quantity of raw gasoline is drawn into the engine by its suction. Various other devices are in use for the same purpose, but in many cases the engine becomes flooded by an overly rich mixture and will not therefore start, 20 and in other cases the mixture is too lean and the engine will not start.

By my invention I am enabled to provide a rich mixture for starting an engine, and thereafter as soon as the charge is fired, I am enabled to 25 automatically cut off the overly rich mixture for starting and thereafter feed a less rich mixture for running the engine until an operative temperature is attained whereby the engine will function without excess fuel for that temperature.

This is principally accomplished by supplying a 30 very rich mixture and suddenly cutting this very rich mixture down to a rich mixture and from thence reducing the richness to normal strength as the engine warms up.

This application is a divisional part of my 35 pending application for patent on Automatic fuel regulators, Serial No. 626,990, filed March 22, 1923, now Patent No. 1,694,801 issued December 11, 1928.

Referring to the drawing in which like numbers indicate the same parts,

Fig. 1 is a view of a device embodying my invention attached to an internal combustion engine.

Fig. 2 is a vertical sectional view of part of 45 the apparatus shown in Fig. 1.

Fig. 3 is a vertical sectional view of another part of the apparatus shown in Fig. 1, and

Fig. 3A is a vertical sectional view of an alternative for the device shown in Fig. 3.

Referring to the drawing, Fig. 1 shows an 50 internal combustion engine having an exhaust pipe 2, an inlet manifold 3 to which is attached a carburetor 4, the carburetor being controlled by the usual throttle valve 5. A vacuum tank 6 is attached to the engine for the purpose of feed-

ing liquid fuel to the carburetor 4 by gravity through a pipe 17, the liquid fuel being drawn from a lower level through a pipe 16 by means of the engine suction which is applied to the vacuum tank from manifold 3 through pipes 7 and 15. 5

The vacuum tank is of well-known construction, such as is known as a Stewart Warner vacuum tank, and this construction need not be described beyond the statement that it contains 10 an inner suction chamber 19 and a liquid reservoir 20, the reservoir 20 being continuously open to atmosphere through a vent 21.

Inserted in the exhaust pipe 2 is an air bulb 13, connected to a Bourdon tube 9 held firmly in 15 a casing 8.

The end of Bourdon tube 9 is formed as a contact adapted to engage an insulated contact 46 carried by the casing 8. The contact 46 is connected by a wire 47 to a solenoid 48 placed in a 20 fitting 49 which is connected through 7 and 15 to the intake 3.

A fuel supply pipe 24 dips below the liquid level A—A in reservoir 20, the fitting 49 and pipe 24 being threaded on to a nipple 50 through which a 25 hollow valve 51 is adapted to slide. The valve 51 has at its upper end a disc 52 and a nozzle 53. A light spring 53a serves to force the valve 51 downwardly when the solenoid 48 is deenergized. The lower part of valve 51 is arranged to be always 30 below the liquid level A—A and is provided with an air vent hole 54 arranged to be below and above the liquid level A—A upon the movement of valve 51 responsive to the action of solenoid 48. A gasket 55 is arranged between disc 52 and 35 solenoid 48 in order to make an air tight seat therebetween.

In place of the Bourdon tube 9, a double diaphragm 9a may be arranged for the same 40 purpose and is an equivalent thereof.

The operation of this modification is as follows:

When the engine is cold, disc 52 is at the bottom of fitting 49 and the current is broken by 45 contact 46 being separated from the end of tube 9, whereby the current cannot be grounded. The lower end of valve 51 therefore is a certain distance below the liquid level of A—A. Upon starting the engine a solid stream of gasoline is drawn 50 through valve 51 and nozzle 53 into the intake manifold 3 through pipe 7 whereby an overly rich mixture causes the engine to fire. The exhaust gases act quickly on bulb 13 whereby the end of the tube 9 causes a circuit to be made by 55 touching contact 46, whereon the solenoid 48

causes valve 51 to jump and seat the disc 52 on the bottom of solenoid 48, an air tight joint being made there by means of gasket 55. The bulb 13 and tube 9 provide an air-tight system which 5 may be filled with air or other suitable gas.

The sudden upward jump of 51 causes air hole 54, which has previously been submerged in the gasoline, to be open to atmosphere admitted to reservoir 20 through vent 21, thereby reducing the 10 amount of gasoline drawn through valve 51 to a rich mixture and at the same time withdraws the vapors of light fractions from 20 and passes them to the engine.

Thereafter, the reduction of the level A—A, 15 caused by the consumption of fuel through carburetor 4, uncovers a further air port 54a whereby the amount of gasoline fed through valve 51 is reduced sufficient to idle the engine, or the proportion may be co-ordinated with that supplied to carburetor 4 to feed a proportion of gasoline and air continuously through valve 51.

In any event the same results are obtained in a different manner as already described, by first 25 providing an overly rich mixture for starting the engine, then reducing the same quickly to a rich mixture and finally reducing the mixture to that required for the normal operation of the engine.

Further, the elements comprising my apparatus are capable of automatic response to temperature, whereby the different proportions of mixture are continued for greater or less periods of time, the same being particularly illustrated 30 by the comparative expansion or contraction of the tube 9, or its equivalents, by heat or cold.

35 Further, it is to be noted that pipe 24 forms a baffle which prevents liquid fuel from splashing on the end of pipe 51 and the air is admitted to the interior of pipe 24 from the vent 21 through the reservoir 20 and holes 56 and 57 which may 40 be placed at varying levels above A—A.

What I claim is new and desire to secure by Letters Patent of the United States is:

1. In an internal combustion engine, the combination of a fuel reservoir, a passageway connecting the engine and reservoir, a valve in the 45 passageway for controlling the supply of fuel

therethrough, means normally positioning said valve for delivering an overly rich mixture to the engine at cranking speeds upon starting it while cold, and thermally controlled electric means for positioning said valve for delivering a rich mixture to the engine when it fires, said means including an encased Bourdon tube having an air bulb responsive to engine generated heat, a solenoid connected to said valve, and an electric circuit, said Bourdon tube being adapted to close 5 said circuit upon firing of the engine, said solenoid being actuated by the closing of the circuit to position the valve for delivering a rich mixture to the engine.

2. In an internal combustion engine, the combination of a fuel reservoir, a passageway connecting the reservoir to the engine, a valve in said passageway for controlling the passage of fuel therethrough and being normally positioned for delivering an overly rich mixture to the engine at 10 cranking speeds upon starting it while cold, a solenoid for adjusting the position of said valve, and thermal means for controlling the actuation of said solenoid, said valve comprising a vertically positioned hollow tube having one end normally positioned below the fuel level in said reservoir, and a plurality of apertures spaced along said submerged end, said solenoid upon actuation being adapted to lift said tube for positioning one of said apertures above the fuel level 20 in said reservoir for delivering a rich mixture to the engine.

3. In combination, an internal combustion engine, a carburetor adapted to supply carbureted air thereto, conduit means for supplying a rich charge to said engine on starting, control means having two positions, the first position being adapted to supply an overly-rich mixture for starting, and the second position being adapted to supply a rich mixture, electrical means for changing said control means from the first position to the second position, and thermo-responsive means adapted to energize said electrical means upon the starting of the engine.

CHARLES L. STOKES.
